UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

HOPPER-ORE-CAR CONSTRUCTION.

1,097,945.

Specification of Letters Patent. Patented May 26, 1914.

Application filed March 14, 1911. Serial No. 614,488.

To all whom it may concern:

Be it known that I, JOHN M. ROHLFING, residing at St. Louis, Missouri, and being a citizen of the United States, have invented 5 certain new and useful Improvements in Hopper-Ore-Car Construction, of which the following is a full, clear, and exact description; such as will enable others skilled in the art to which it appertains to make and 10 to use the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

In said drawings: Figure 1 is a side elevational view of a car embodying the features of my invention. Fig. 2 is an enlarged end view thereof. Fig. 3 is a longitudinal sectional view taken on the plane of line 3—3, Fig. 1. Fig. 4 is a detail sectional view, similar to a portion of Fig. 3, 20 but the parts being seen on an enlarged scale. Fig. 5 is a detail illustrating the relative positions of the several plates, of which the opposite sides of the car are composed. Fig. 6 is an edge view of the 25 plates shown in Fig. 5, looking at Fig. 5 from the right-hand side thereof toward the left-hand side. Fig. 7 is a fragmentary elevational view of a portion of the car structure. Fig. 8 is a vertical sectional view of 30 the parts seen in Fig. 7, the section being taken on the plane indicated by line 8—8 of said figure. Fig. 9 is an enlarged sectional view illustrating the connections between 35 the end plates and the end frames of the car, the view being taken approximately on the plane indicated by line 9—9 of Fig. 1.

The object of this invention is to provide a hopper bottom car without the use of the customary longitudinal center sills extending 40 below the body of the car, and thus to secure sufficient unobstructed space, at the bottom of the hopper portion thereof, for an unusually large discharge door opening, and further to provide in such car an all-metal 45 construction which shall possess sufficient longitudinal rigidity to withstand the severe buffing and pulling stresses to which cars of this class are subjected in use.

A further object is to provide a car in 50 which practically the entire weight of the

body portion and of the lading carried thereby is transmitted to the side girders and from the opposite ends of said side girders directly to the adjacent ends of the bolsters, thence to the center bearings and 60 trucks. Such a disposal of the weights renders it possible to employ an underframe structure comprising only a pair of end frames. These end frames, indicated generally by the reference character 1 in the 65 drawings, but described and claimed in detail in a separate application, Serial Number 614,490, filed of even date herewith, are so arranged and the parts of the car body adapted to engage them, are so designed that 70 the end frames may be entirely completed before being connected to the finished car body. The connection of the body portion of the end frames with the body portion of 75 the car is not intended to act as a support for any portion of the weight of the car body except through the side girders or sides of the car, but is designed simply as a means of securing a rigid structure under all conditions, and further as a means of maintaining the end frame against the natural 80 tendency to tilt upward at the forward end when being subjected to a slight collision. This tendency is due incidentally to the presence of a certain amount of elasticity in 85 the metal of the bolster, which elasticity would permit a limited degree of bending in the bolster so that the rear end of the end frame, unless securely fastened to the adjacent inclined end plate of the car body, 90 would naturally be subjected to a slight downward movement along the inclined face of said plate. It will be seen from the above also that the rigid connection of the end frame with the car body, while it is not intended as a support for said car body, nevertheless 95 serves to reinforce the bolster in absorbing the shocks of impact.

Each of the end frames comprises a body portion 1, in which there are provided draft 100 sills 1^a with laterally extending arms or body bolsters 3, disposed in the plane of said draft sills. The outer, or free, ends of each of the extensions 3 of one of the end frames 1 are connected with the respective outer 105 ends of the extensions 3 of the other end frames by the side plates, or girders, 4 of the car body. The draft sills, bolsters and side girders are rigidly connected so as to utilize the side girders in resisting buffing 110

stresses. For this purpose the side girders lap and are rigidly secured to the outer ends of said bolsters, the bolsters in turn being connected to the draft sills in any convenient manner to cause said elements to work together in resisting buffing stresses. The inner ends of the body portions of each of the end frames are beveled to correspond with the angle of inclination of the adjacent end plate 5 of the hopper to the under faces of which they are securely fastened, as best seen in Fig. 3 in dotted lines and in Fig. 9 in full lines.

Each of the side girders 4 of the car is composed of a plurality of plates as 6, 7 and 8. (See Fig. 5). These plates are arranged, and are rigidly secured together, by suitable stiffening and strengthening members as follows:—The plates 6 and 7 are identical in shape but are placed end to end in the structure, and the outer end of each is beveled to correspond to the angle of the inclination desired for the end sheets of the hopper. The plate 8 is arranged beneath the plates 6 and 7 and its length is only slightly less than the combined length of the plates 6 and 7 at their top edges. In the structure the plate 8 extends from extension 3 of one of the end frames to extension 3 of the other end frame and its upper edge laps and is fixed to the lower edges of the plates 6 and 7 by rivets as at 9. The lower edges of the plates 6 and 7 are inset so as to preserve a smooth exterior.

Riveted to the lower edge of the plate 8, and extending throughout the full length thereof, is a stiffening angle 10. The angle 10 is disposed with its vertical flange upstanding and lying flat against the outer face of the plate 8 and with its horizontal flange projecting outwardly from the extreme lower edge thereof. At each of its ends the angle 10 is connected, by its horizontal flange, to an under-lapping lip 11 provided upon the ends of the respective extensions 3 of the end frames. The vertical flange is fixed by rivets to the end walls of said extensions, said rivets passing through the lower edge of the adjacent portions of the plate 8.

Extending vertically downwardly from the aligned upper edges of the plates 6 and 7 and arranged to cover the abutting edges of said plates, is a stiffening angle 12. The angle 12 extends downwardly beyond the lower edge of the plates 6 and 7, across the outer face of the plate 8, to a point slightly above the top of the angle 10, where it is bent inwardly, through an inverted L-shaped slot 13 formed in said plate 8. The inwardly bent portion of this stiffening member extends downwardly, below the plane of the lower longitudinal stiffening angle 10, for a purpose presently to be set forth.

Arranged parallel with the stiffening

angle 12 and fixed to the outer faces of the plates 6, 7 and 8, at points spaced upon each side of said angle, are stiffening angles 14—15. These last mentioned stiffening angles are of equal length with the angle 12 and slots as 16—17, similar to the slot 13, are formed in the plate 8 for their passage through said plate 8 in a manner similar to that described for the angle 12.

A pair of oppositely disposed reinforcing angles as 17^a is arranged at the point of each of the slots 13, 16 and 17. These angles are each arranged with one of their flanges lying flat against the side of the car and with the other flanges outstanding and said outstanding flanges of each pair are disposed to lie with their upper ends flat against the opposite sides of the outstanding flange of the adjacent vertical stiffening angle and be secured thereto by through rivets as at 17^b. The outstanding flanges of each pair are connected together, near their lower ends, beneath the bend in the said stiffeners, by rivets as at 17^c. A suitable washer or filler as 17^d is placed between the opposite faces of the outstanding flanges of the angles 17^a at the lower end so as to compensate for the thickness of the interposed flange of the vertical stiffeners at the upper end. The flanges of each of the angles 17^a, which are arranged to lie flat against the outer face of the adjacent portion of the plate 8 as stated, are securely riveted thereto and the lower portion of each is offset so as to overlap and be riveted through the upwardly extending flange of the longitudinal angle 10 fixed to the bottom of the plate 8.

Stiffening angles 18 and 19 are secured, each by one of its flanges to the outer faces of the plates 6 and 7 respectively, and to portions of the plate 8. The remaining flange outstands from the face of said plates. These stiffeners extend from the top edge of the car, at a point adjacent the upper end of the vertical stiffeners 14 and 15, obliquely downward to the ends of the respective bolster extensions 3, where they are each bent to a perpendicular as at 18^a and secured as follows:—The outstanding flange of the portion 18^a lies flat against an outstanding vertical lip 20, formed integral with, or fixed to, the outer face of the end wall of the bolster extension 3, and is riveted thereto. Above the lip 20 said outstanding flange is further connected to the extension 3 by rivets through a rib 21 formed integral with, or fixed to, the upper face of the extension 3 and projecting outwardly beyond the outer face of the end wall thereof. The flange which lies flat against the outer face of the plates is secured by rivets extending through the plate 8 and through the end wall of the extension 3.

The upper corners of the opposite ends of

the plate 8 are cut away to correspond with the angle of inclination of the stiffeners 18-19. A relatively short reinforcing angle 22 is secured to each of the stiffeners 18 and 19 at points extending from the upper face of the respective extensions 3 to the top of the plate 8, at which points said stiffeners 18 and 19 engage the plates 6 and 7. The angles 22 are bent to conform to the shape of the lower ends of the stiffeners and are secured to the inner faces thereof by rivets extending through the adjacent flanges of the stiffening and reinforcing angles and through the intervening portions of the plate 8. The lower ends of the inwardly projecting flanges of the angles 22 are securely riveted to the ribs 21, comprising angle sections secured to the upper faces of the outer ends of the bolster extensions 3.

The juncture between the upper edge of the plate 8 and the lower aligned edges of the plates 6 and 7 is suitably reinforced by a stiffening member 23. This reinforcing member is composed of a series of angle sections as 23^a, 23^b, 23^c, and 23^d, each arranged with one of its flanges cutstanding along its upper edge and with its other flange depending therefrom and lying flat against the outer faces of the plates, and covering the juncture between said plates. The depending flange of each section is secured by rivets passed therethrough and through the lapping edges of the plates 6-8 and 7-8. The section 23^a extends from the vertical stiffener 14 to the stiffener 18 and has its outer end offset so as to overlap, and be riveted to, the flange of the stiffener 18. The section 23^b extends from the stiffener 14 to the stiffener 12 and has each of its ends offset so as to overlap, and be riveted to, the flanges of said stiffeners. The section 23^c extends from the stiffener 12 to the stiffener 15 and has one of its ends offset to overlap, and be riveted to, the flange of the stiffener 15. The section 23^d, extends from the stiffener 15 to the stiffener 19 and has its outer end offset to overlap, and be riveted to, the flange of the stiffener 19.

An inclined hopper plate as 24 is fixed, by rivets as at 25, to the inner face of the plate 8 upon each side of the car, and rests with its under or outer face lying flat upon, and riveted to, the upper face of the inwardly and downwardly inclined portions of the vertical plate girder stiffeners 12, 14 and 15. (See Fig. 8.) Each of the plates 24 is formed of two sections, one upon each side of the central stiffener 12 to which they are connected similarly as are the plates 6 and 7 above.

A horizontally disposed stiffening angle as 26 is fixed, by one of its flanges, to the outer or under face of the lower edge of the plate 24. The other flange of said angle 26 projects outwardly and downwardly from

the upper edge of said first mentioned flange and the lower end of the stiffeners 12, 14 and 15 are made to project downwardly into contact with the top surface thereof. The opposite ends of the plate 24 are beveled to correspond with the angle of inclination of the end sheets of the hopper and said beveled portions are arranged as a continuation of the adjacent beveled ends of the plates 6 and 7.

Each of the inclined end hopper plates 5 extends from the horizontal plane of the upper edge of the plates 6 and 7 downwardly to the horizontal plane of the lower edge of the side hopper plates 24. Their opposite sides are turned inwardly as at 27 and lap and lie flat against the adjacent inclined edges of the side plates of the cars to which they are securely riveted. The lower end of each of the end plates 5 is narrowed and the lower portions of the in-turned side flanges 27 thereof are caused to stand at an incline, corresponding with the angle of inclination of the adjacent side hopper plate 24. The lapping edges of the plates 24 with the flanges 27 are securely riveted together.

Fixed, by one of its flanges, to the under face of each of the end plates 5 is a stiffening I-section 28. These I-sections extend vertically from top to bottom of said sheets, and spaced upon both sides thereof in planes parallel therewith, are stiffening channel sections 29. The stiffeners 29 are substantially of the same length as the stiffeners 28 and each has its flanges facing away from the respective I-sections and is fixed, by one of its flanges, to the adjacent end plate 5.

Supporting channels as 30 and 31 are arranged one at each end of the car, disposed transversely thereof with their opposite ends resting upon the upper outstanding flanges of the inclined portions of the stiffeners 18 and 19 and are connected to said flanges by rivets extending through the webs of the channels. The flanges of the channels 30 and 31 project upwardly and the webs of the channels are in direct contact with the flanges of the stiffeners 18 and 19, one of the flanges of each of the supporting channels 30 and 31 is disposed so as to engage the outer flanges of the vertical stiffeners 28 and 29, attached to the respective end sheets, to aid in rigidly supporting said end plate and stiffeners against sagging under load and to effectively transport all weight to the side girders.

A reinforcing supporting angle as 32 is arranged parallel with, and above, each of the channels 30 and 31 and said angle 32 is fixed by rivets, through its vertical flange, to the outer flanges of the stiffeners 28 and 29. The opposite ends of each of the supports 32 beyond the stiffeners 29 are bent to correspond to the shape of the end of the

130

hopper and are extended and lapped over the side plates thereof, as at 33, in an inclined plane parallel to the respective stiffening angles 18 and 19 and are extended to 5 the upper edge of said side plates. The portions of the angles 32 which overlap the side plates of the car are securely riveted to said side plates.

A reinforcing angle 34 is fixed to the top 10 edges of the hopper side and end plates. The angle 34 extends entirely around the car and is made up of two side and two end portions. The end sections are extended around the opposite corners and are connected to the adjacent ends of the side sections by suitable splice plates as at 35. Each section of the member 34 is arranged with one of its flanges outstanding and overlapping the upper edge of the adjacent hopper plate and with its other flange depending, and being riveted to the inner face of the upper edge of said plates.

A gusset plate as 36 is positioned in the angle formed by each of the bolster extensions 3 and the adjacent portion of the side girder plates 8. Each of these gussets is fixed to the upper surface of the extension 3 by suitable rivets and to the plates 8 by rivets passed through depending flanges 30 formed upon said gusset.

The upper end of each of the end frames 1, where it engages the plate 5 of the hopper, is of a width sufficient to extend, transversely of the car, from one of the end plate stiffeners 29 to the other, and the opposite side walls thereof as 3^a are securely riveted, as at 37, to the inner faces of the webs of said stiffeners. (See Figs. 3 and 9). The end wall as 3^b of each of the end frames is 40 riveted directly to the end plate. A depression 38 is formed in said end wall 3^b to receive the central end plate stiffener 28 and the bottom wall as 3^c of said depression is riveted, as at 39, to the outer flange of said 45 stiffener.

The construction of the side girders as described and the nature of their connection with the end frames, is of sufficient strength to transmit all buffing and pulling stresses 50 from one end of the car to the other, without the necessity for the customary longitudinal center sills. From the construction described it will be apparent that the discharge-door opening extends, in length, 55 practically from the inner end of the end frame at one end of the car to the inner end of the end frame at the opposite end of the car and, in width, from the lower edge of one of the side hopper plates 24, to the other. In this connection, it should be 60 stated that the plates 24 are inclined so as to space their lower edges inwardly from the vertical plane of the adjacent side girders a distance only sufficient to accommodate 65 the mechanism necessary for the operation

of the doors, Nos. 40, 41, 42 and 43. The specific form of these doors and the various details of their construction and of the mechanism for operating them are fully disclosed in a separate application, and said doors are 70 illustrated, in the present application, only sufficiently to define their general location and arrangement.

Having thus described my invention, what I claim as new and desire to secure by Letters Patent is:—

1. A car construction comprising in combination, bolsters, inclined end walls, side plate girders forming the only side sills of said car and having projecting portions 80 lapping and rigidly secured to the ends of said bolsters, and flanged members resting on said projecting portions extending across said end walls and serving as connectors for said girders and supports for said end 85 walls.

2. A car construction comprising in combination, bolsters, end walls, side plate girders forming the only side sills of the car between said bolsters and having integral portions extending in part beyond 90 said end walls, and supporting means for said end walls resting on said extending portions and serving as means for connecting said side girders relatively above said 95 bolsters.

3. A car construction comprising in combination, bolsters, obliquely extending end walls, a stiffening member for said end walls extending obliquely parallel therewith, side 100 plate girders lapping and rigidly secured to the end portions of said bolsters and forming the side sills of the car, said bolsters extending in part beyond said end walls, and means resting on the extending 105 parts of said girders connected with said girders and said stiffening member and serving as supports for said end walls.

4. A car construction comprising in combination, bolsters, oblique end walls, a stiffening member for said end walls extending obliquely parallel therewith, side plate girders lapping and rigidly secured to the end portions of said bolsters and forming the side walls of the car, said girders extending in part beyond said end walls, and a transversely extending channel resting on the extending parts of said girders, uniting said girders above and independent of said 110 bolsters and assisting to support said end 115 walls.

5. In a car construction, side plate girders comprising a plurality of plates which are of unequal length longitudinally of the car, draft sills, bolsters rigidly connected to and 120 between the lower ends of said girders in the plane of said draft sills, sloping end sheets, stiffening members extending obliquely upwardly beyond said bolsters, and a plurality of supports for said end sheets 125 130

- and stiffening members lapping said girders and being connected therewith above said bolsters.
6. In a car, bolsters, plate girder side walls lapping the bolsters at their lower end portions and having portions above said bolsters of less length than the distance between the bolsters, and transversely extending braces resting on and connecting said lower portions relatively above the bolsters.
7. In a car construction, compound plate girders comprising upper and lower plate portions forming the car sides, hopper plates fixed to the lower plate portions, and reinforcing members uniting and penetrating the girders and fixed to said hopper plates.
8. In a car construction, a plate girder comprising a pair of vertically divided plates, a single plate lapping the first mentioned plates, a hopper plate connected above the bottom of the single plate, and a pair of reinforcing members lapping and projected through said single plate and connected with said hopper plate.
9. In a car construction, a plate girder comprising a pair of vertically divided plates, a single plate lapping the first mentioned plate, a hopper plate connected above the bottom of the single plate, and a plurality of reinforce members lying in direct contact with the face of the pair of plates and the hopper plate.
- 35 10. In a car construction, the combination of bolsters, inclined end walls, and side walls in the form of compound girders divided vertically and horizontally, the lower girder portion forming a continuous tension member for the compound girder, said compound girders lapping and being rigidly secured to said bolsters.
- 45 11. In a car construction, the combination of bolsters, inclined end walls, and side walls in the form of compound girders divided vertically and horizontally, the lower portions of the girders forming continuous tension members for the compound girders, said compound girders lapping and being rigidly secured to said bolsters.
- 55 12. In a car construction, the combination of bolsters, inclined end walls, and side walls in the form of compound girders comprising single lower plates and a plurality of upper plates lapping said lower plates, tension members for the compound girders, and means resting on said lower plates for reinforcing the end wall said compound girders lapping and being rigidly secured to said bolsters.
- 65 13. In a car construction, the combination of bolsters, inclined end walls, and side walls in the form of compound girders having end extensions, with end wall supports carried by said end extensions.
14. In a car construction, the combination of bolsters, end walls, and a side wall in the form of a compound plate girder, the lower portion of said plate girder being continuous and projecting beyond the end wall and acting as a tension member for the compound girder, and an end wall supporting member carried by the projection of the lower girder portion, said compound girders lapping and being rigidly secured to said bolsters.
- 70 15. In a car body, parallel side plate girders each formed of three separate plates lapping and connected along horizontal and vertical lines, side hopper plates connected to the inner faces of said plate girders and continuous end plates extending below the side girders and connected directly thereto and to said side hopper plates.
- 80 16. In a car body, parallel side plate girders each formed of three separate plates lapping and connected along horizontal and vertical lines, side hopper plates connected to the inner faces of said plate girders, and continuous end plates formed with curviform end portions, said end plates extending below the side girders and connected directly thereto.
- 90 17. In a car body, plate girder side walls, a continuous end wall with curviform end portions lapping and connected directly to said side walls, side hopper-plates connected to an intermediate portion of the plate girder sides and reinforce members projected through the side girders and connected directly with the side girders and said side hopper-plates.
- 100 18. A car structure comprising a body portion formed with side walls and an end wall, a plurality of inclined reinforcing members fixed to said end wall extending from top to bottom thereof, and a transverse reinforcing member connecting said inclined members and having its opposite end portions bent so as to overlap said side walls, said overlapping portions being inclined upwardly and terminating adjacent the upper edges of said side walls.
- 110 19. A car structure comprising a body portion formed with side walls and inclined end walls, a plurality of reinforcing members fixed to said end walls extending from top to bottom thereof, and transverse reinforcing members connecting said end wall reinforcing members and having their opposite end portions bent so as to overlap said side walls, said overlapping portions being inclined upwardly and terminating adjacent the upper edges of said side walls.
- 120 20. A car structure comprising a body portion formed with side walls and an end wall, a pair of inclined reinforcing channel members fixed by one of their flanges to said end wall, extending in parallel relation from top to bottom and spaced from oppo-

site edges of said end wall, and a transverse reinforcing member connecting the outer flanges of said channel members, said transverse member having intermediate portions bent toward said end wall to conform to the end of the hopper and opposite end portions lapping and fixed to said side walls.

21. A car structure comprising a body portion formed with side walls and an end wall, a pair of inclined reinforcing channel members fixed by one of their flanges to said end wall, extending in parallel relation from top to bottom and spaced from opposite edges of said end wall, the opposite edge portions of said end wall being bent so as to lap parts of said side walls, and a transverse reinforcing member connecting the outer flanges of said channels, said transverse members having intermediate portions bent toward said end walls to conform to the end of the hopper and opposite end portions lapping the bent portions of said end wall and being fixed to said side walls.

25 22. A car structure comprising a body portion formed with side walls and inclined end walls, the opposite edge portions of said end walls being bent so as to lap parts of said side walls and form a rounded corner, reinforcing members fixed to the upper edges of said end walls, having their end portions bent so as to lap portions of the opposite side walls and being fixed throughout their length to said end walls and side walls, reinforcing members fixed to the upper edges of said side walls between the ends of said first mentioned reinforcing members and splice parts connecting the abutting ends of all of said reinforcing members.

23. In a car structure, a body portion comprising inclined end walls, vertical side walls and inclined side hopper plates, vertical stiffeners fixed to said side walls and extended through said side walls and being fixed to said side hopper plates.

24. In a car structure, a pair of end

frames, a car body comprising inclined end walls, vertical side walls and inclined side hopper plates, said side walls comprising girders adapted to support the car body upon the end frames and being formed with a top chord and a bottom chord, vertical stiffeners fixed to said side walls and extended through said side walls adjacent the lower chords thereof and being fixed to said side hopper plates.

25. In a car structure, a pair of end frames, a car body comprising inclined end walls, vertical side walls, said side walls comprising girders adapted to support the car body upon the end frames and being formed with a top chord and a bottom chord, inclined side hopper plates fixed to said side walls above said bottom chord, and vertical stiffeners fixed to said side walls and extended through said side walls and being fixed to said side hopper plates.

26. In a car structure, a pair of end frames, a car body comprising inclined end walls, vertical side walls, said side walls comprising girders adapted to support the car body upon the end frames and being formed with a top chord and a bottom chord, inclined side hopper plates fixed to the inner side of said side walls above said bottom chord and vertical stiffeners fixed to the outer side of said side wall, and being fixed to said side hopper plates.

27. In a car construction, the combination of bolsters, end walls, and side walls in form of compound trusses, means uniting the end walls and the upper portions of the trusses, and means uniting the end walls and the lower portions of the trusses, the upper of said means being in tension and the lower of said means in compression.

In witness whereof I have hereunto set my hand in the presence of two witnesses.

JOHN M. ROHLFING.
